UTILITY TRUCK

Paul E. Hawkins, Lakewood, Ohio, assignor to
The Baker-Raulang Company, Cleveland, Ohio,
a corporation of Ohio

Application August 4, 1937, Serial No. 157,400

10 Claims.

(Cl. 228—6)

This invention relates to a utility truck, more particularly to the mounting thereon and control of an extensible ladder.

One object of the invention is to provide an improved ladder mounting, whereby the ladder may be readily swung bodily into various angular positions and also tilted at desired inclinations to permit of a wide range of operations.

Another object of the invention is to provide for an extensible ladder an auxiliary member, movably mounted on one of the ladder sections, whereby the ladder, when in one position, may be used as an operating platform.

Another object of the invention is to provide an improved ladder construction and mounting therefor having a counterbalance and mechanism for locking and controlling the movement of the ladder in either or both directions of movement.

Other objects of the invention will be apparent to those skilled in the art to which my invention relates from the following description taken in connection with the accompanying drawings, wherein

Fig. 1 is a side elevation of a truck embodying my invention.

Fig. 2 is a rear elevation.

Fig. 3 is a fragmentary section on the line 3—3 of Fig. 1, enlarged.

Fig. 4 is a fragmentary section on the line 4—4 of Fig. 2, enlarged; but showing the auxiliary member in operative position.

Fig. 5 is a section on the line 5—5 of Fig. 4, but showing the brake shoes in applied position.

Fig. 6 is a fragmentary view of the outer end portion of the extensible ladder section, parts being broken away.

Fig. 7 is a fragmentary view on the line 7—7 of Fig. 6.

Fig. 8 is a view on the line 8—8 of Fig. 2; but showing the parts in full lines.

Fig. 9 is a fragmentary view of parts shown in Fig. 10, portions being broken away.

Fig. 10 is an end view of the parts shown in Fig. 9.

Fig. 11 is a section on the line 11—11 of Fig. 9.

Fig. 12 is a fragmentary side elevation showing the step and its mounting on the extensible ladder section.

Fig. 13 is an end elevation of parts shown in Fig. 12.

Fig. 14 is a section on the line 14—14 of Fig. 12, portions being broken away.

Fig. 15 is a detail view.

Fig. 16 is a fragmentary view showing the latching device between the ladder sections.

Fig. 17 is a fragment view showing a modification.

In the drawings, 1 indicates as an entirety a power driven truck having front steerable wheels 2 and rear driven wheels 3, which support a suitable frame, the latter providing a platform 4 on its rear portion. Mounted on and incorporated with the frame is a suitable driver's seat preferably enclosed in a cab 5, and rearward of the cab 5 and housings 6 arranged adjacent the opposite sides of the platform 4. The cab 5 and housings 6 may be of any desired construction. By preference, the housings 6 are divided into compartments of various sizes with provision for access thereto on their inner or outer sides; hinged doors 6a being shown in Fig. 1. The cab 5 may be omitted; or the cab and housings may be fabricated as a unitary structure.

7 indicates an upright tubular member having at its lower end a base 8, which is suitably bolted to the platform 4. The upper end of the tubular member is closed by a plug or wall 9 having an upwardly extending stud shaft 10, in axial relation to the tubular member 7. The shaft 10

forms a seat for the inner race of an anti-friction bearing 11. 12 indicates a sleeve surrounding the upper end portion of the tubular member 7, the lower end of the sleeve rotatively engaging a bushing 13 provided on the tubular member. The upper end of the sleeve 12 telescopes into a collar 14, to which it is suitably secured. The collar 14 is formed integrally with a plate 15 formed with an opening 16, the walls of which form a seat for the outer race of the bearing 11. An annular member 17 is disposed

in engagement with the inner bearing race and in overlapping relation to the plate 15, and a nut 18 engaging the threads on the outer end of the shaft 10, holds the bearing 11 in position and the sleeve 12 and plate 15 in rotatable relation to the tubular member 7, so that the sleeve may rotate on the bushing 13 and bearing 11. The plate 15 is provided with diametrical arms 18' (preferably formed integrally therewith) which

terminate in alined hollow bosses 19. The bosses 19 support a rod 20 which extends laterally therebeyond to provide trunnions or pivots on which a ladder, indicated as an entirety at 21, is fulcrumed intermediate its ends, whereby it may

be tilted at various inclinations, as shown in dotted lines in Fig. 2. It will thus be seen from the foregoing description that the ladder 21 is capable of being bodily tilted about the axis of the rod 20 and swung about the axis of the tu-

5

bular member 7, this latter movement permitting the ladder to be extended over a vehicle parked on the street to enable the mechanic to reach a pole and lamps and other equipment thereon mounted on the side of the roadway.

The ladder 21 comprises a main section 22 and an extensible section 23, each section consisting of side rails 24 and suitable rungs 23a. As shown in Fig. 4, the rails 24 of the section 23 are disposed within and guided by the rails 24 of the main section 22 and slide on the rungs of the latter section, being held in sliding engagement with these rungs by angles 25 fixed to the inner sides of the rails 24 of the main section. The inner side of each rail 24 of the ladder section 23 is provided with a suitable dog 24a arranged to engage any one of the rungs 23a of the ladder section 22 when the section 23 is moved upwardly. The dog 24a is provided with a pivoted element 24a' arranged to engage the rungs of the section 22 in the downward movement of the section 23 and cause the dog 24a to ride the rungs. The dogs 24a are of well known construction. The rails 24 of the main section are provided along their lower end walls with channels 26 each of which is secured in position by a plate 27 fixed to the outer side of the adjacent rail and having a portion bent under and secured to the channel. As shown in Fig. 4 the side walls 30 of channels 26 and plate 27 are formed with aligned openings to receive the outer ends of the rod 20 to fulcrum the ladder 21 thereon.

Mechanism is provided for automatically locking the ladder 21 in any position to which it may be tilted or raised, so that when the ladder reaches the desired position no manual operation is required to prevent it from swinging downwardly. This mechanism comprises two telescoping members, one consisting of a ratchet 28 and the other a guide 29 for the ratchet and carrying a dog 30, normally biased into engagement with the ratchet 28. By preference, the outer end of the ratchet 28 is suitably fixed to a web 31, which in turn is welded or otherwise secured to a rod 32 supported in aligned openings formed in the channels 26 and the outer end of the guide 29 is pivotally supported on the outer end of a bracket 33, the bracket having a hub 33a, surrounding and fixed to the sleeve 12. The guide 29 consists of a tubular member (of rectangular shape in cross section) suitably connected at its lower end to a casting 34. The casting terminates in a hollow boss 34a, through which a pin extends to pivotally connect the casting to the walls of the bracket 33. The dog 30 is pivotally mounted on a shaft 30a and normally biased into engagement with the ratchet 28 by a spring 35 coiled around a rod 36, pivoted to the dog at its inner end and slidably guided by the walls of an opening 37 formed in the rear wall of the guide member 29. The rear end of the dog 30 is provided with a pair of spaced arms 38, between which operates a cam 39, to engage one arm 38 to lock the dog in engagement with the ratchet 28 (see Figs. 9 and 11) and to engage the other arm 38 to hold the dog 30 in an inoperative position. The cam 39 is fixed to a rock shaft 40 mounted in the walls of the guide member 29, one end of the shaft 40 being provided with a crank 41 by means of which the cam 39 may be operated to either position. When the cam 39 is in the position shown in Fig. 9, the dog 30 is in locked relation to a tooth of the ratchet 28, so that the outer end of the ladder cannot be raised or lowered in a vertical plane. If the cam 39 is

moved to its mid or neutral position (see dotted line position of the crank 41 indicated at x), the ladder 21 may be tilted upwardly and in such movement the ratchet 28 would be moved endwise in its guide and the nose of the dog 30 would ride the ratchet. To permit tilting of the ladder downwardly, the crank 41 is operated to the position shown in dotted lines at x', which operation moves the dog 30 away from and maintains it out of engagement with the ratchet 28.

To lock the ladder 21 in any position to which it may be swung laterally I provide the following: 5
42 indicates a substantially bell-shaped member 10
the side wall 42a of which serves as a brake drum 15
arranged to be engaged by a pair of brake shoes 43. The bottom wall of the member 42 is bolted 20
to the flange of the hub 33a so as to have fixed 25
relation to the sleeve 12. The corresponding 30
ends of the brake shoes 43 are provided with a 35
hollow boss 43a mounted on a pin 44 depending 40
from one edge of a plate 45 having a collar 46, 45
which is suitably fixed to the tubular member 7. The 50
boss 43a is cut through on its inner wall to 55
permit the shoes to move into and out of 60
engagement with the wall 42a. The opposite ends 65
of the brake shoes 43 are pivoted to a pair of piv- 70
otally connected levers 47, 47', constituting a 75
toggle. The levers 47, 47', are connected to the 80
upper end of a rod 48, the lower end of which 85
is pivoted to a foot lever 49, fulcrumed on the 90
base 8, whereby the levers 47, 47', may be oper- 95
ated to apply and release the shoes 43. When 100
the lever 49 is operated downwardly (such posi- 105
tion of the lever being shown in Figs. 4 and 5), 110
the toggle levers 47, 47', are expanded to apply 115
the brake shoes 43 to the drum 42a, the effect 120
of which is to lock the ladder 21 in any predeter- 125
mined position against swinging movement later- 130
ally about the axis of the column 7. Operation 135
of the lever 49 upwardly releases the brake shoes, 140
to permit swinging movement of the ladder. A 145
plate 46a is suitably secured by cap screws to the 150
collar 46 and carries a projecting lug 46b to limit 155
the upward movement of the toggle levers 47, 47'. The 160
lever 47' consists of two parts, one threaded 165
into the other to provide for adjustment of the 170
levers.

50 indicates an auxiliary member extending 50
substantially from end to end of and swingably 55
mounted on the ladder section 22, and adapted 60
to be positioned on or over the ladder section 23 65
(see Figs. 1 and 4). Accordingly, when the ladder 70
is in a substantially horizontal position and 75
swung laterally (see dotted lines in Fig. 2) and 80
operations are to be carried out upon pole sup- 85
ported lamps or other overhead equipment and 90
apparatus at the outer end of the ladder or inter- 95
mediate its ends, the auxiliary member 50 serves 100
as a walk for the mechanic or operator so that 105
he can readily traverse the ladder 21 from end to 110
end, instead of attempting to tread the rungs. 115
The auxiliary member may consist of a frame 120
formed of channel members 51 between which is 125
mounted a sheet of wire mesh material 52, adapt- 130
ed to serve as the walk or tread surface. The 135
marginal or edge portions of the sheet material 140
52 are secured to the channel members in any 145
desired manner. The auxiliary member 50 is pro- 150
vided along one side with a plurality of hinge 155
members 53, suitably secured to a hollow rod 54, 160
which rotates in a plurality of brackets 55 carried 165
by the adjacent rail 24 of the ladder section 22, 170
whereby the auxiliary member may be swung into 175
an upright position against a guard 57, as shown 180
in Fig. 3. The hinge members 53 are shaped to 185
75

provide an off-set portion 53a, so as to extend over the adjacent rail 24 of the ladder section 23, whereby the auxiliary member 50 may rest on the rungs 23a thereof. When the auxiliary member 50 is in its inoperative position, the ladder section 23 may be extended relative to the section 22 and both sections used in the usual way. I preferably provide a guard along either side of the ladder section 22. Each guard 57 consists of a hand rail 58, supported and braced by a plurality of rods or standards 59, 59' suitably secured to the adjacent rail 24 of the ladder section 22. Between and connected to certain of the rods 59 of the guard 57 adjacent to the rod 54 I provide a spacing rod 60, on which is fulcrumed a rocker 61, having a catch 61a at one end arranged to engage the auxiliary member 50 and lock it to the guard, as shown in Fig. 3. The rocker 61 is preferably biased into locking position by a coiled spring 62. The other end of the rocker 61 is connected to a pull rod 63, whereby it may be released from the auxiliary member 50.

64 indicates an auxiliary guard mounted on the outer end of the ladder section 23. The guard 64 consists of a loop formed of suitable piping covered with rubber or other insulating material. The guard 64 is provided at its sides with arms 65, pivoted on the outer ends of the rails 24 of the ladder section 23, a projection 66 on each rail 24 serving to limit the outward movement of the guard and a pin 67 movably mounted in an opening formed in one rail 24 serving to limit the inward movement of the guard. The pin 67 is disengageable from the guard arm so that the guard may be swung or folded down on the rails 24 of the ladder section, as shown in dotted lines in Fig. 6. A spring 68 may be coiled around the pin 67 between the projecting end of one of the reinforcing plates 69 on the end of the adjacent rail 24 and a lug 70 on the pin for normally projecting the pin outwardly into operative position, as shown in Fig. 7; the lug 70 being adapted to operate as a handle for the pin to disengage it from the adjacent arm 65.

45 Rearward of one housing 6 I may provide a seat 70' and rearward of the other housing I provide a ladder 71 to facilitate access to the ladder 21. As shown in Fig. 1, the tubular member or column 7 is arranged on the platform 4 rearward of the housings 6, so that the ladder 21 may be operated into various positions without interference therewith.

As will be understood from Fig. 2, (a) the guard 64 occupies a substantially upright position, when the ladder 21 is disposed horizontally so that the mechanic cannot fall off the outer end of the ladder and (b) when the ladder is tilted and the mechanic is standing on a step 73 (later referred to) carried by and between the rails of the ladder section 23 near its outer end, the guard surrounds the mechanic so as to insure his safety in this position.

The step 73 (shown particularly in Figs. 12 to 15, inclusive) comprises a plurality of spaced slats or bars 74 connected together at their opposite ends by channels 75 and end bars 75a and connected together intermediate their ends by a cross member 76 having pairs of spaced transverse walls 76a. The walls 76a of each pair are formed with aligned openings to receive a shaft 77 fixedly supported at its outer end in the adjacent rail 24 of the ladder section 23. The shafts 77 are mounted in alinement and serve as a fulcrum for the step 73. The step 73 is 75 swingable from a position aligned with the ladder

rails (see dotted lines in Figs. 1 and 12), which may be termed its inoperative position, to any angular position relative thereto, so that when the ladder is tilted to any predetermined position and the section 23 is extended, the step 73 may 5 be operated to a horizontal position, so that the mechanic may stand on the step. Means are provided for locking the step 73 in its inoperative position or in any operative position in angular relation to the ladder section 23, such means 10 shown herein for illustrative purposes comprising the following: 78 indicates plates secured to the inner sides of the rails 24 of the ladder section 23 and having arcuate end walls 78a concentric to the axis of the shafts 77, each formed 15 with a series of notches 79, each notch in one plate being aligned with a notch in the other plate. 80 indicates a spring operated member arranged to engage any two aligned notches to secure the step in the desired fixed relation to 20 the ladder rails. The member 80 comprises a cross rod 81 disposed transversely of the step 73 and a rod 82 connected at one end to the rod 81 and extending longitudinally of the step. Below and at the opposite sides of the step adjacent 25 its inner end I provide blocks 83 formed with aligned slots 84 extending parallel to the step, the opposite end portions of the rod 81 extending through the slots 84 so that their free ends may be removably seated in any two aligned notches 30 79. The rod 82 extends through and is endwise movable in an opening 85 formed in the cross member 76. A coiled spring 86 coiled around the rod 82 and interposed between the cross member 76 and a bead 87 on the outer end of the rod, 35 serves normally to bias the member 80 in a direction outwardly of the step 73, so as to maintain the bar 81 in the aligned notches corresponding to the position to which the step is adjusted. A handle 88 suitably secured to either or both of 40 the rods 81, 82, may serve as a means for removing the rod 81 from any two aligned notches and holding it outwardly of the arcuate walls 78a while the step is being moved or adjusted from one position to another position.

The outer end portion of the ladder 21 may be counterbalanced in any desired manner; for example, by means of a weight 89, as shown in Fig. 1, or by means of an expansion spring 90, as shown in Fig. 17. In this latter arrangement 50 I provide a pair of telescopically related tubular members 91, 92, the former being pivoted to the bracket 33 and the latter member being pivoted to a cross rod 93 mounted at its ends in the channels 26, the opposite ends of spring 90 abutting 55 against the end walls of the members 91, 92, and normally tending to move the latter endwise outwardly. Suitable means (not shown) may be provided for adjusting the tension of the spring.

To those skilled in the art to which my invention relates many changes in construction and widely differing embodiments and applications of the invention will suggest themselves without departing from the spirit and scope of the invention. My disclosures and the description herein 65 are purely illustrative and are not intended to be in any sense limiting.

What I claim is:

1. In a vehicle, the combination of a platform thereon; a column mounted on said platform, 70 supporting means comprising a plurality of members arranged to be assembled in superposed relation, the lower member being mounted to swing laterally about the axis of said column and to be tilted in vertical planes, the intermediate 75

member being movable endwise on said lower member and the upper member being hingedly connected along one longitudinal side to one side of said lower member outwardly of said intermediate member for movement to an inoperative position outwardly of said lower and intermediate members.

2. In a vehicle having a platform thereon, the combination of a column on said platform, a ladder mounted to tilt and swing laterally on said column and comprising a main section and a separate section normally disposed in superposed relation to said main section, said separate section being slidable endwise on said main section, and a walk extending longitudinally of said ladder and arranged to normally lie on said separate section, said walk being hinged along one side to one rail of said main section whereby it may be swung to an inoperative position at one side of said main and separate sections.

3. In a vehicle having a platform thereon, the combination of a column on said platform, a ladder mounted to tilt and swing laterally on said column and comprising a main section and a separate section normally disposed in superposed relation to said main section, said separate section being slidable endwise on said main section, and a walk extending longitudinally of said ladder and arranged to normally lie on one of said sections, said walk being hinged along one side to one rail of said main section whereby it may be swung to an inoperative position at one side thereof.

4. A vehicle as claimed in claim 3, wherein the walk consists of a frame and wire screen material connected along its marginal portions to said frame.

5. A vehicle as claimed in claim 2 wherein the side rail to which the walk is hinged is provided with latching means for holding said walk in its inoperative position.

6. In a vehicle having a platform thereon, the combination of a column on said platform, a ladder mounted to tilt and swing laterally on said column, a guard secured to and extending longitudinally of said ladder, a walk extending longitudinally of said ladder and hinged along one side to one rail thereof, said walk being arranged to lie on said ladder and to be swung to an inoperative position, and means carried by said guard for holding said walk in its inoperative position.

7. In a vehicle having a platform, the combination of a column thereon, a ladder comprising a main section mounted to tilt and swing laterally on said column and a separate section the side rails of which are disposed within the side rails of said main section and slidably engage the rungs thereof for movement endwise, a walk extending longitudinally of said sections and arranged to lie on said separate section, and hinge elements between one side of said walk and the adjacent rail of said main section, to permit said walk to swing to an inoperative position, said hinge elements having off-sets extending over the adjacent side rail of said separate section.

8. In a wheel mounted frame, a platform thereon, a column on said platform, a ladder mounted to tilt and swing laterally on said column and comprising a main section and a separate section slidable thereon, a guard secured to and extending longitudinally of said main ladder section, a walk extending longitudinally of said separate ladder section and hinged along one side to one rail of said main ladder section, said walk being arranged to lie on said separate ladder section and to be swung to an inoperative position, and means carried by said guard for securing said walk in its inoperative position.

9. In a wheel mounted frame, a platform thereon, a column on said platform, a ladder mounted intermediate its ends on said column to tilt and swing laterally, a walk extending longitudinally of said ladder and hinged along one side to one rail of said ladder, said walk being arranged to lie on said ladder and to be swung bodily laterally to an inoperative position at one side of said ladder, whereby the rungs of said ladder are unobstructed from end to end thereof, and means for holding said walk in its inoperative position.

10. In a vehicle having a platform thereon, the combination of a column on said platform, a ladder mounted to tilt and swing laterally on said column, a guard secured to one side of said ladder and extending longitudinally thereof, a walk extending longitudinally of said ladder and hinged along one side to one rail thereof, said walk being arranged to lie on said ladder and to be swung bodily laterally to an inoperative position at one side thereof, and means for holding said walk in its inoperative position.

PAUL E. HAWKINS.
